UNITED STATES PATENT OFFICE.

CHARLES GUILLAUME PETIT, OF BELLEVUE, FRANCE.

PRODUCTION OF SAFETY-GROUNDS FOR DOCUMENTS.

1,153,131.

Specification of Letters Patent.

Patented Sept. 7, 1915.

Application filed October 11, 1911. Serial No. 654,428.

To all whom it may concern:

Be it known that I, CHARLES GUILLAUME PETIT, of 10 Rue Dumont d'Urville, Bellevue, Department of Seine et Oise, Republic of France, have invented certain new and useful Improvements in the Production of Safety-Grounds for Documents, of which the following is a full, clear, and exact description.

10 This invention relates to safety-grounds for bank-notes, share-certificates and other valuable papers or documents of any kind.

It consists in reproducing by means of two or more half-tone or line-screens of different line-inclinations or different designs 15 and with different lengths of exposure, a half-tone pattern arranged so as to present most diverse gradations in such a way as to vary the thickening or thinning of the lines, 20 dots or grains furnished by the screens, then forming by means of each photographic print so obtained blocks, plates or reproductions adapted to print by any usual method, and lastly printing the safety- 25 ground my means of the latter with colors selected so that decomposition of the image obtained becomes substantially impossible.

By reason of the possibility of varying at will the gradation of the half-tones of the 30 pattern and therefore the thickness of the screened lines, dots or grains, and owing to the difference of inclination or design of the screens, there are obtained new decorative effects which can be varied at will, and the 35 reproduction of which is impossible; the invention, therefore, offers complete protection against falsifications or forgery.

For the preparation of the pattern serving to obtain the variable thickening or 40 thinning of the lines, dots or grains of the screens, there is employed the following process which by reason of its simplicity, its low cost of working and the guarantees against falsification which it presents, forms 45 an essential part of the invention. It consists in employing a nonactinic (black, yellow, orange, etc.) paper or equivalent material which is perforated more or less symmetrically to produce a design which, al- 50 though coarse, may yet be agreeable to the eye. The perforations are formed in the paper or other material in any suitable manner, for example by means of a hollow punch, but the perforations are made of 55 different sizes and of different shapes in order that in the operation to be hereafter

described the light may act to a greater or less degree but for the same length of time upon the sensitive preparations. The perforated paper so obtained is used like a 60 photographic negative which it is desired to reproduce upon sensitized paper; that is to say, it is placed in a printing-frame, but very slightly separated from the sensitized paper by means of an intermediate sheet of 65 clear glass. A ground glass is placed at the front of the printing frame and the whole is exposed to the light of the sun or of one or more electric lamps, taking care not to leave the frame more than a few seconds in 70 the same position and taking away the ground glass from time to time.

The intensity of the image is judged as is usual in printing on paper, by opening the frame when it is thought that the desired effect is nearly reached. The light 75 passing through the perforations in the different positions in which the printing frame is held under the source of light causes an innumerable quantity of tones of an original decorative effect, because the luminous rays falling sometimes directly, sometimes obliquely, upon the perforations produce at certain points crossings of intense light upon the sensitive surface, while other 80 parts are less exposed and others again are wholly concealed. The whole of this operation with ground glass, direct light and movement of the frame and of the glass is intended to obscure or render indefinite the 85 image of the perforation in such a way that it is impossible to state from what geometric figure it proceeds or to repeat the same image twice. If necessary the operation 90 might be performed without the ground glass by means of diffused light and without moving the printing-frame.

When the desired effect is obtained, the sensitized paper is withdrawn from the frame, washed and fixed in the usual manner. It is evident that the image obtained in the manner described can in no way be repeated a second time, especially if the perforated paper is destroyed after a satisfactory decorative result has been obtained. Consequently the method affords a complete protection against falsification. The pattern thus formed is twice reproduced at different angles by means of copying line-screens and by the usual printing methods 105 (copper-plate, typography, lithography, etc.). The result is obtained by means of 110

substantially differing times of exposure for the preparation of the screened negative blocks, so that one of them reproduces the whole of the image and the other gives only the dark half-tones and the blocks. In these conditions when printing takes place, if one of the blocks is printed for example in yellow and the other in red, the resulting orange will be formed only in the dark half-tones and the two superposed impressions will provide soft and iris-like effects, the decomposition and reconstruction of which are impracticable. This affords a fresh protection against falsification.

15 In the accompanying drawing is shown in cross section a printing frame by which the pattern may be obtained.

As here shown the frame *b* has an inwardly projecting bead at the front in which a horizontal slot is provided to permit the temporary adjustment of a sheet of ground glass *a*. A sheet of clear glass *c* rests against the inner face of the bead and supports the perforated negative *d*. Several sheets of clear glass *e*, *e*¹, *e*² separate this from this sheet *f* of sensitized paper, which is held in position by the back of the frame *g*.

The invention is not limited to the above described details of execution. For example, two or more differently perforated patterns might be used and the screened or half-tone blocks obtained separately therefrom might be printed one upon the other. Again the perforated patterns might be replaced by photographic prints or negatives or any compositions adapted to serve as such, maintained at a distance from the sensitized paper. Moreover, there may be

printed upon the safety-grounds obtained in the manner above described, either at 40 once or at the same time as the letter-press, any border, ornamentation or the like that may be desired as a third impression.

Having thus described my invention, what I claim as such and desire to secure by Letters Patent is:—

1. As a new article of manufacture, a sheet of suitable material having printed thereon a safety ground of the character described comprising superposed impressions of indeterminate iris-like outlines of diverse light gradations, said impressions being in different colors and screen schemes, the whole forming upon the sheet an image having blended colors and indeterminate outlines practically incapable of lineal decomposition.

2. As a new article of manufacture, a sheet of suitable material having printed thereon a safety ground for bank notes and the like, comprising a half-tone composed of a plurality of superposed images each of indefinite and vague and uncertain outline having light gradations varying from positive and strong effects to vague and confused and disappearing effects, the superposed images being differently colored and the colors effecting a finished blend.

In testimony whereof I have signed my name to this specification, in the presence of two subscribing witnesses.

CHARLES GUILLAUME PETIT.
